UNITED STATES PATENT OFFICE.

WILLIAM H. ROSE, OF JERSEY CITY, NEW JERSEY.

CONTAINER AND CLOSURE THEREFOR.

Application filed July 20, 1928. Serial No. 294,238.

My invention relates to containers and closures for the same and refers particularly to containers and container closures so related to each other in construction as to allow of their easy and effective co-operation to produce a closed container.

One of the objects of my invention is a container closure capable of adjustment upon a container and of closing the same in an effective manner by the simple process of passing, or forcing, a closed ring thereon.

Among the attributes desirable in a closure of this character may be mentioned the following:—It should be economic in production and simple in construction, it should not puncture or destroy the container walls, it should be capable of adjustment without the employment of tools, it should not crush or destroy the shape of the container walls through compression or otherwise, it should be free from accidental displacement, it should produce a firm and effective closure of the container, it should be capable of ready removal without injuring the container.

The device of my invention possesses all of the above-mentioned, and other, valuable attributes as will be evident upon a consideration of my specification and its accompanying drawings.

In the accompanying drawings illustrating modified forms of the device of my invention similar parts are designated by similar numerals.

Figure 1 is a side view of a container closed by one form of my closure.

Figure 2 is an enlarged fragmentary view of a portion of Figure 1.

Figure 3 is a section through the line 3—3 of Figure 2.

Figure 4 is a section through the line 4—4 of Figure 2.

Figure 5 is a fragmentary vertical cross-section of a modified form of my device.

Figure 6 is a fragmentary front view of a modified form of my device.

Figure 7 is a section through the line 7—7 of Figure 6.

Figure 8 is a section through the line 8—8 of Figure 6.

Figure 9 is a plan view of the binding ring of my device.

The particular form of the device of my invention illustrated in Figures 1, 2, 3 and 4 comprises an annular container 10 of card-board, fiber, wood or other suitable material

having an annular recess, or groove, 11 therein.

A separable cover, or closure, comprises the annular base 12 having the annular U-shaped flange with the inner vertical member 13, the upper horizontal member 14 and the outer vertical member 15.

The annular flange member 15 has a plurality of depending tongues 16, 16, each of which is cut to form the outwardly extended upper stop 17 and an inwardly extended locking member 18, the lower portion of each tongue being extended outwardly forming a lower stop 19.

The locking member 18 is formed by cutting three sides of a central portion of a tongue 16 and bending the thus cut portion inwardly, each locking member 18 being positioned to enter the groove 11 when the cover is in proper position upon the container 10.

In order to employ the device, the cover flange 15, or the tongues 16, 16 are sprung outwardly, if necessary in order to allow the cover to be placed upon the container as shown, and the binding ring 20 is then forced downwardly over the cover, forcing the locking members 18, 18 into the groove 11 of the container 10, the stops 17 and 19 preventing the accidental displacement of the ring 20. The resiliency of the metal cover will spring the upper stop member into outward position after the ring 20 has passed thereover.

I prefer to have the groove 11 in practically the plane of the base 12, in order to assist in supporting the inward pressure of the cover at this point.

In the modification of the cover of my invention illustrated in Figure 5, each upper stop 21 is formed by pressing a portion of a tongue 16 outwardly instead of forming it by cutting as shown in Figures 1, 2, 3 and 4.

In the modification of the cover of my invention illustrated in Figures 6, 7 and 8, each tongue has an upper stop 22 formed by pressing a portion of the tongue outwardly, a lower stop 19 formed by bending the end of the tongue outwardly and two locking members 23, 23, formed by cutting the sides of the tongue and bending the cut portions inwardly.

It will thus be seen that the device of my invention presents a container and a cover, or closure, therefore, the locked closing of the container being accomplished by plac-

- ing the cover upon the container and forcing a closed binding ring thereover, the binding ring being protected from accidental displacement.
- 5 It will be noted that the cover can be placed in any position upon the container, as the continuous groove 11 will receive the locking members at any point thereof and it will be noted further that no incisions are 10 made in the side walls of the container by the cover in order to retain it in position, thus maintaining the full original strength of the container wall.
- It will be further noted that in the forms 15 illustrated the inward pressure of the binding ring is in line with the base of the cover, thus preventing the inward crushing of the container when it is composed of fiber or other crushable material.
- 20 I do not limit myself to the particular size, shape, number, arrangement or material of parts as shown and described as these are given simply as a means for clearly describing the device of my invention.
- 25 What I claim is:—
1. In combination with a container having a recess in the outer face of the side wall thereof, a closure comprising a base, a U-shaped peripheral flange carried by said base capable of placement in abutment with the upper portion of a container wall, retaining said base in the plane of said recess, a plurality of depending tongues carried by said flange, an extended locking member 30 carried by each tongue capable of being placed within said container recess, a closed ring capable of being forced downwardly over said tongues forcing said locking means into said container recess and means 35 preventing the accidental displacement of said ring.
  2. In combination with a container having a recess in the outer face of the side wall thereof, a closure comprising a base, a U-shaped peripheral flange carried by said base capable of placement in abutment with the upper portion of a container wall, re- 40 taining said base in the plane of said recess, a plurality of depending tongues carried by said flange, an extended locking member 45 integral with each tongue capable of being placed within said container recess, a closed ring capable of being forced downwardly over said tongues forcing said locking means into said container recess and means 50 preventing the accidental displacement of said ring.
  3. In combination with a container having a recess in the outer face of the side wall thereof, a closure comprising a base, a U-shaped peripheral flange carried by said base capable of placement in abutment with the upper portion of a container wall, retaining said base in the plane of said recess, a plurality of depending tongues carried by said flange, an extended locking member 55 integral with each tongue capable of being placed within said container recess, a closed ring capable of being forced downwardly over said tongues forcing said locking means into said container recess and means 60 preventing the accidental displacement of said ring.
  4. In combination with a container having a recess in the outer face of the side wall thereof, a closure comprising a base, a U-shaped peripheral flange carried by said base capable of abutment upon the upper portion of a container, retaining said base in the plane of said recess, a plurality of 65 depending tongues carried by said flange, an inwardly extended locking member formed by a cut-out portion of each tongue capable of placement within said container recess, a closed ring capable of being forced downwardly over said tongues forcing said locking member into said recess and outwardly extended means formed by cut-out portions of each tongue preventing the accidental 70 displacement of said ring.

Signed at New York city in the county of New York and State of New York this 19th day of July, 1928.

WILLIAM H. ROSE.
